UNITED STATES PATENT OFFICE.

MIGUEL AGUSTIN GLYNN, OF HAVANA, CUBA.

RAILWAY-TIE.

SPECIFICATION forming part of Letters Patent No. 317,763, dated May 12, 1885.

Application filed September 6, 1884. (No model.)

To all whom it may concern:

Be it known that I, MIGUEL AGUSTIN GLYNN, of Havana, Cuba, have invented a new and useful Improvement in Railway-Ties, of which 5 the following is a full, clear, and exact description.

The object of my invention is to construct railway-ties of metal for cheapness and durability, and also to make them with means for 10 securing the rails that will allow the removal of one or more ties from the road-bed and their renewal without disturbance of the others or the rails. To these ends I combine with metallic ties of suitable form fastening devices that receive and lap over the rail-flanges, which flanges are notched, as hereinafter 15 described and claimed.

Reference is to be had to the accompanying drawings, forming part of this specification, 20 in which similar letters of reference indicate corresponding parts in all the figures.

Figure 1 is a longitudinal sectional elevation of a railway-bed, showing the improved ties. Fig. 2 is a plan view of the same. Fig. 25 3 is a cross-section, and Fig. 4 a side view, of the tie in modified form; and Fig. 5 is an end view of tie constructed for use as a longitudinal sleeper, and Fig. 6 is a longitudinal view of the same.

30 A is the tie, formed of sheet or wrought metal struck up or rolled into the U form shown in Figs. 1 and 2, and made with flanges a on its edges extending outward, so as to give a broad bearing, and to prevent the tie being forced down by weight or pressure. The 35 flanges also prevent, by the weight of the ballast on them, any rising or springing of the tie.

Upon the upper side of the tie are flanges or ribs b, that are formed with or attached to the 40 tie by any suitable means, and these flanges are cut or formed to lap upon the flanges of the rail B, so as to hold the latter securely down to place. The flanges of the rail are notched at each side at c, or there may be 45 one notch of sufficient length in one flange, as at c', so that the rail can be set down upon

the tie, the flanges or fastenings b passing through the notches, and then by an endwise movement of the rail or sidewise movement of the tie the fastenings b will be locked over the 50 solid portion of the rail-flanges. In Figs. 3 and 4 the tie is in the form of an inverted T, with the web slotted at d to receive the rail-flanges in the same manner.

In Fig. 5 the tie A has hook-shaped fingers 55 b', attached by riveting or otherwise, so as to receive the rail between them. In this figure the fastening devices b' are placed to adapt the tie for use as a longitudinal sleeper, but they may be applied to cross-ties. 60

In order to remove a tie from the road-bed, it is only necessary to remove the ballast for a short distance, and then move the tie sidewise until the fastenings are over the notches in the rail-flanges, when the tie can be dropped down 65 and drawn out endwise. A new tie can then be inserted and the whole operation carried out without disturbing the rails, and as easily as with wooden ties.

I am aware that it is not new to construct 70 ties of sheet metal of V or semi-cylindrical form and notch or cut out the upper side to receive the rail, or to provide movable fastenings for the rail. In such cases the rail has not a solid support on account of the opening 75 made in the tie. In my tie the upper side is formed with a solid rib, and the rib is notched to form the hook-shaped fastenings, so that the tie proper is left intact to support the rail.

Having thus described my invention, what 80 I claim as new, and desire to secure by Letters Patent, is—

The combination of a metallic tie provided with fastenings that receive and lap over the rail-flanges and a rail having flanges notched, 85 substantially as described.

MIGUEL AGUSTIN GLYNN.
